SOUND FILM REPRODUCING APPARATUS

John C. Davidson, Brooklyn, N. Y., assignor to
Electrical Research Products, Inc., New York,
N. Y., a corporation of Delaware

Application December 19, 1936, Serial No. 116,686

4 Claims. (Cl. 179—100.3)

This invention relates to sound film reproducing systems and more particularly to improvements in apparatus employed in such systems.

At the present time, the sound record portion 5 of sound picture films for theater reproduction may bear either the present standard single track sound record or one of several sound records comprising two separate adjacent tracks. One sound record of the double track type is known as a 10 push-pull sound record which consists of two separate adjacent tracks in which the two half-waves of the sound wave are recorded 180 degrees out of phase. Another sound record of the double track type is known as a stereophonic sound record in which the separate adjacent tracks represent the same sound waves as recorded from 15 different positions with respect to a single sound source. A further record of this type is known as a split frequency record in which each track 20 is a record of sound frequencies within a certain frequency band included in the recorded sound.

To reproduce from the present standard single track sound record only one light sensitive element in a reproducing circuit is necessary. However, in reproducing from a double track sound record, it is necessary that each record be projected to a separate light sensitive element and that these light sensitive elements, in the case of a push-pull sound record, be connected in push-pull 25 arrangement with a current responsive device in the reproducing circuit. Present standard theater reproducing apparatus is not capable of reproducing a double track sound record and to provide separate sound reproducing apparatus for the reproduction of this type sound record would obviously be impractical from a commercial standpoint. It is therefore desirable that theater sound film reproducing apparatus be capable of 30 reproducing either a double track sound record or the present standard single track sound record.

It is the object of this invention to provide a sound film reproducing apparatus capable of reproducing either standard single sound track or double track sound records.

45 A feature of the invention lies in the provision of means whereby the transfer from one type of reproduction to the other may be readily effected without altering the position or adjustment of the essential electrical and optical elements of 50 the reproducing system.

A further feature of the invention lies in the provision of a single control means for producing operation of all the elements necessary in the transfer from one system of reproduction to the 55 other.

The invention will be more readily understood by reference to the accompanying drawing in which:

Fig. 1 is a side elevation of the sound reproducing portion of a sound picture reproducer disclosing the interior of the film driving compartment and the photoelectric cell compartment;

Fig. 2 is a view, partly in section taken through line 2—2 of Fig. 1;

Fig. 3 is a section taken through line 3—3 of Fig. 2; and

Fig. 4 discloses a preferred form of circuit for coupling the photosensitive element to a reproducing circuit for the reproduction of a push-pull sound record.

Fig. 1 discloses the sound reproduction portion of a sound picture reproducing apparatus comprising a compartment 1, which houses the film driving mechanism and a compartment 2, which houses the photoelectric cell and the elements included in the photoelectric cell coupling circuit to the reproducing apparatus. Compartment 1 contains a constant speed film driving sprocket 3 and a take-up sprocket 4, both driven from a motor M by means of suitable gearing, not shown. 25 Pivoted film retaining rollers 5 and 6 insure engagement of film F with the sprockets 3 and 4 respectively. Numeral 7 denotes a freely rotatable film engaging drum which is secured to a shaft, the other end of which supports a suitable 30 flywheel (not shown). Pivoted film retaining roller 8 retains the film F on the drum 7.

The film F is fed from a picture projecting compartment 9 of the apparatus to the sound reproducing compartment where it engages in succession the film-driven drum 7, sprocket 3 and sprocket 4. Rotation of the drum 7 and its associated flywheel is produced by movement of the film F in response to the driving action of sprocket 3. The film may be adjusted laterally by means 40 of roller 8 so that the marginal edge of the film bearing the sound track will overhang one edge of the drum 7. The film F is fed from the take-up sprocket 4 to a take-up reel located in a reel housing 10.

A lamp 13 is secured in an adjustable mounting 45 14 in compartment 1. A combination condenser lens and double prism unit 15 projects light rays from lamp 13 to the over-hanging edge of film F on the roller 7. The unit 15 includes one prism which deflects the light rays inwardly toward the rear wall of housing 1 and a second prism which deflects these light rays to the overhanging sound record portion of the film F on roller 7. Lenses located in a lens tube 16 project a magnified 50 55

image of the sound record to a fixed slit in slit assembly 17. A photoelectric cell 18 receives the record modulated light rays projected through the fixed slit in slit assembly 17.

5 While applicant mentions various types of double track sound records capable of use on sound picture films for theater reproduction, his drawing discloses a reproducing circuit and switching arrangement to be employed in a sound reproducing system for the reproduction of a standard single sound record or a push-pull sound record. His invention, however, may be applied to reproducing systems in which reproduction is obtained from a standard single track 10 sound record and any or all of the double track records mentioned above. Suitable coupling circuits and switching arrangements may be provided for coupling the two photosensitive elements in parallel to a single current responsive device 15 and for coupling each photosensitive elements to a separate current responsive device included in separate reproducing channels for the reproduction of stereophonic and split frequency sound records.

20 In the reproduction of a standard single track sound record, the image of the single film record is projected to a single light sensitive element. However, the push-pull sound record consists of two adjacent records located in the same film 25 area as the single standard record and each of these separate records must be projected to a separate light sensitive area. Two separate photoelectric cells may be used and means may be provided in the form of deflecting prisms between the film and the cells for deflecting each record image to a separate one of the photoelectric cells. The preferred arrangement, however, is to employ a double photoelectric cell contained 30 in a single envelope.

35 Difficulty has been encountered in obtaining distortionless reproduction from a double track sound record using either two separate cells or a double unit cell due to the projection of the light rays from one record onto the adjacent photosensitive area which should receive only light rays from the other record. This difficulty is caused either by the slight transverse weaving of the film as it passes over the flywheel drum 7 or by slight misalignment of the sound record throughout the 40 complete film length.

45 In accordance with this invention these difficulties are eliminated by providing means in the form of a mask 20 which may be moved into the optical system to mask a small area in the center 50 of the light beam when reproducing a double track sound record. This mask 20, in this disclosure, is movably mounted in the slit assembly 17 in a manner to be described.

55 In Figs. 1, 2 and 3 the slit assembly 17 comprises a circular member 21 provided with an aperture 22. Member 21 is provided with grooves to receive slidable slit forming members 23 and 24. A second circular member 25 is provided with an aperture 26. Member 25 is also provided with a groove to receive the slidable mask 20. Members 21 and 25 are held together as a unit by means of screws 27 (Fig. 2). The size of the slit may be adjusted by slit forming members 23 and 24 and these members may be held in adjusted 60 position by means of set screws 28 and 29. The mask 20 has a slot 30 to provide clearance for the screw 29. The entire unit is mounted in an annular supporting member 31 having an integral arm secured to the inner wall of housing 65 70 2 by means of machine screws 32 (Fig. 1). The

75 slit assembly 17 may be rotated in the holder 31 to provide for azimuth adjustment of the slit and may be held in adjusted position by means of a set screw 33 (Fig. 2) mounted in member 31.

80 Fig. 4 discloses a circuit coupling the photoelectric cell 18 to a current responsive device in the input of a sound reproducing circuit. The current responsive device disclosed in the drawing is a transformer T. The photocell 18 preferably comprises two cathodes 34 and 35 and two 85 anodes 36 and 37 enclosed in a common envelope. Polarizing potential for the photocell is obtained from a potential source A.

90 A switch 38 provided in the coupling circuit permits the several elements of the double photoelectric cell 18 to be suitably connected to the primary of transformer T for either push-pull or standard reproduction. A switch blade 39 has conducting end portions 40 and 41 separated therefrom by suitable insulating material. The 95 switch blade is secured to a shaft 42.

100 As shown in Fig. 4 the switch is in position for standard reproduction. In this connection the two separate anodes 36 and 37 are connected in parallel to one side of the transformer primary 105 and the mid-point connection of the upper half of the transformer primary is connected to the positive terminal of the potential source A. The cathodes 34 and 35 are connected to the negative terminal of potential source A. The circuit is 110 from the positive terminal of potential source A, lead 43, upper half of primary of transformer T, lead 44, resistance 47, anode 36, cathode 34, lead 48 to the negative terminal of potential source A. Cathode 35 is connected through lead 48 to negative terminal of source A and anode 37 is connected to lead 46 through lead 49, switch contacts 50 and 51 and lead 52.

115 Operation of switch blade 39 in a clockwise direction connects the separate anodes 36 and 37 120 to opposite sides of the transformer primary and the mid-point of the transformer primary to the positive terminal of the potential source A for push-pull operation. The circuit from the negative terminal of potential source A is through 125 lead 48, cathodes 34 and 35, and anodes 36 and 37. Anode 36 connects through resistance 47 and lead 46 to one side of the transformer primary. Anode 37 is connected to the opposite side of the 130 transformer primary through lead 49, contact 50, switch blade 41, contact 53, resistance 54 and lead 55. The switch blade contact 40 bridges contacts 56 and 57 of the switch to connect the mid-point of the primary of the transformer through lead 45 to the positive terminal of source A.

135 Resistances 58, 59 and 60 and condensers 61 and 62 constitute elements of a filter which furnishes the final filtering of the polarizing potential for the cell 18.

140 Referring to Fig. 2, the switch 38 is mounted in the base of an enclosure 65. The switch shaft 42 extends through the upper wall of the enclosure 65 and is rotatable in a bushing 66 which is provided with an external screw thread to receive nut 67. The switch shaft 42 is provided 145 with an operating arm 68 having a knurled handle 69 which extends through a small opening 70 in a removable partition 71. The compartment 2 may be completely closed by a door 72 hinged at 73 (Fig. 1).

150 A sleeve 75 fits over shaft 42 and has a flanged end 76 which rests on nut 67. A nut 77 having a flanged portion 78 engages the externally threaded upper portion 79 of nut 67 to hold sleeve 75 in place. Sleeve 75 is provided with a cut-out 75

portion (not shown) to give clearance to the operating arm 68. The upper end of member 75 is provided with a slot 80.

A sleeve 81 fits over sleeve 75. A pin 82 passes through the slot 80 in member 75 and has its ends secured in member 81. Member 81 is provided with a spiral slot 83 through which the switch operating arm 68 extends. A mask engaging member 85 is adjustable along the upper end of member 81 and may be secured in adjusted position by means of set screw 86. Member 81 is provided with a groove 87 to receive the lower flanged end of mask 20 (Fig. 3).

In the position shown in the drawing, both the reproducing optical and electrical systems are adjusted to reproduce from a standard single track sound record. Movement of the operating arm 68 to the left (Fig. 1) will produce clockwise movement of switch blade 39 to provide a push-pull connection between the photosensitive elements and the current responsive device in the reproducing circuit. The operating arm 68 in moving to the left will bear against the upper edge of spiral slot 83 in member 81, which, being held against rotative movement by pin 82 in slot 80, will move vertically upward to effect an upward movement of mask 20 into the area of the slit formed by members 23 and 24.

It is apparent from the foregoing that applicant has provided a sound picture projecting system in which the optical and electrical systems may be altered without effecting adjustment of the essential elements of each system to reproduce either single track or double track sound records and in which the number of operations necessary to effect a change from one system to the other is reduced to a minimum.

What is claimed is:

1. In a sound film reproducing system having means for projecting a beam of sound modulated light, in combination, a plurality of photosensitive elements disposed in the path of the beam projected by said means, means movable into said light beam to mask a portion thereof projected to said photosensitive elements, an electrical circuit including said photosensitive elements, a current responsive device and a switching means, and a common operating means for said masking means and said switching means.

2. In a sound film reproducing system having means for projecting a beam of sound modulated

light rays, in combination, a photoelectric cell having a plurality of light sensitive elements disposed in the path of said light beam, an electrical circuit including said photoelectric cell and a current responsive device, means in said circuit for changing the circuit arrangement between said light sensitive elements and said current responsive device, means movable into said projected beam to mask the center portion thereof projected to said photoelectric cell, and a unitary control means for said switching means and said masking means.

3. In a sound film reproducing system, having means for projecting a beam of sound modulated light, in combination, a plurality of photosensitive elements disposed in the path of said beam, an opaque mask movable into the path of said beam to mask the center portion thereof, an electrical circuit including said photosensitive elements, a current responsive device, and a switch, said switch being operable to alternatively connect said photosensitive elements in parallel arrangement or a push-pull arrangement with said current responsive device, operating means for said switch, and means associated with said switch operating means for moving said masking means into the path of said projected light beam when said switch is operated to effect a push-pull connection between said photosensitive elements and said current responsive device and to withdraw said masking means from the path of said projected beam when said switch is operated to effect a parallel connection between said photosensitive elements and said current responsive device.

4. The combination in a sound film reproducing system, means to project a beam of modulated light, a plurality of photosensitive elements disposed in said projected beam, means movable into said beam to mask a portion thereof, an electrical circuit including said photosensitive elements, a plurality of current responsive devices and a switching means, said switching means being operable to alternatively connect all said photosensitive elements in parallel with a single one of said current responsive devices or each photosensitive element individually to a separate one of said current responsive devices, and a unitary control means for said switching means and said masking means.

JOHN C. DAVIDSON.
